UNITED STATES PATENT OFFICE.

GILBERT E. GA NUN, OF MOUNT KISCO, NEW YORK, ASSIGNOR OF ONE-HALF TO ASA YOUNG, OF SAME PLACE.

COMBINED SOFA AND BATH-TUB.

SPECIFICATION forming part of Letters Patent No. 294,460, dated March 4, 1884.

Application filed March 19, 1883. (No model.)

To all whom it may concern:

Be it known that I, GILBERT E. GA NUN, a citizen of the United States, residing at Mount Kisco, in the county of Westchester and State of New York, have invented certain new and useful Improvements in Combined Sofa and Bath-Tub; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a front view of my sofa. Fig. 2 is a rear view. Fig. 3 is a cross-sectional view of the same. Fig. 4 is a vertical sectional view of the boiler.

This invention has relation to baths; and it consists in the construction and novel arrangement of a bath-tub in the body portion of a sofa under a removable seat, and in providing in connection therewith a water-tank and a boiler, all is hereinafter set forth.

In the accompanying drawings, the letter A designates the body-frame of the sofa, and B its back. In the body-frame is seated and supported a metallic tub, C; or a wooden bath-tub may be constructed in the body-frame and lined with thin metal.

D represents a lid or cover for the tub C, which is designed to rest upon the marginal portion of the frame A, and is usually formed with an under projection, e, which is designed to fit within the upper portion of the tub, and serves to hold the cover or seat in place thereon. The cover D may be upholstered, as indicated at F, the springs resting on the cover. The back B and arm G of the sofa may also be upholstered, so that the sofa will form a handsome and convenient article of furniture when not in use as a bath.

H indicates an elongated tank of metal, which is connected to the back B of the sofa, being usually seated in an elongated recess, K, in the back, so that it is out of sight when the sofa is placed against the wall. From the tank a pipe, a, extends into the bath-tub, ter-

minating in a faucet, b. From the reservoir extend two pipes, c and c', one at a higher level than the other, said pipes being designed to provide means of communication with the boiler, respectively, as shown at I and I'. This boiler is designed to heat the water in the tank in a rapid manner. It consists in a hollow or double-wall skirt-cylinder, m, a series of double-wall cones, n, one above another, within the skirt-cylinder, and a larger double-wall cone, d, located above the smaller cones, and spreading over the top of the skirt-cylinder. The cones and cylinder are boiler-sections, and they are connected to each other by means of short pipes or passages in the following manner: From the apex of each cone-chamber a short passage, p, extends upward to the central portion of the concave bottom of the cone next above it. The apex-pipe q of the large, or top cone-chamber is designed to be connected to the upper pipe c of the tank. From the central or highest portion of the bottom of the lower cone extends a pipe, r, which is connected to the lower pipe, c', of the tank.

The boiler is designed to be heated by means of an ordinary oil-stove, and rapidly heats the water in the reservoir or tank, which circulates through the boiler.

When the bath is not in use, the boiler may be removed, and the seat or cover D having been placed on the bath-tub, the sofa-bath becomes an ordinary article of furniture.

It is not intended that the boiler shown and described should be claimed in the present application, as any ordinary tank or boiler may be used instead; but the right is herein reserved to make a separate future application therefor.

Having described this invention, what I claim, and desire to secure by Letters Patent, is—

1. A sofa and bath-tub combined, wherein the bath-tub is located and supported in the body-frame of the sofa, and the seat thereof forms a cover for the bath-tub, concealing it from view, substantially as specified.

2. The combination, with a sofa having a bath-tub in its body portion, and a removable seat, of a water tank or reservoir attached to the back of the sofa, substantially as specified.
- 5 3. The combination, with a sofa having a bath-tub and water-tank provided with a faucet extending into the tub, of a water-heating attachment, substantially as specified.

In testimony whereof I affix my signature in presence of two witnesses.

GILBERT E. GA NUN.
